SHIRT BODY PRESSING MACHINE

Louis N. Strike, Salt Lake City, Utah

Application May 11, 1953, Serial No. 353,979

9 Claims. (Cl. 223—57)

This invention relates to a machine for pressing the bodies of shirts or the like.

An object of the present invention is to provide an improved machine that has a reciprocating buck or form on which a shirt or similar garment is adapted to be draped and automatic mechanism, set into operation by a simple push button control, to move the draped buck from dressing to pressing position, couple the buck to a source of compressed air while in the latter position to both distend and dry and press out the sides and the yoke of the shirt, bring a pair of steam-heated pressing platens into pressing engagement with the front and back of the shirt while in said pressing position, and, finally, either by a push on a second control button or by operation of time-control means, separating the platens and returning the buck to dressing position.

In the interest of simplicity, the front and back of the buck are flat, enabling flat draping of the front and back of the shirt thereon, and the pressing platens are also flat so as to have pressing engagement only with the flat faces of the buck. Therefore, the sides and yoke of the shirt are not engaged by the platens. In order that these latter parts of the shirt be ironed in a wrinkle-free manner and, moreover, to insure thorough ironing of the shirt yoke which is usually of two plies of material, it is another object of the invention to provide the buck with side and yoke distendable or inflatable and air-permeous members and to introduce into said members, while the front and back of the shirt are being pressed by the platens, heated air at a suitably high pressure that will pass through said members and the portions of the shirt held distended thereby to iron the latter portions from within as effectively as if ironed or pressed by an outwardly applied heated platen.

Accordingly, it is a further object of the invention to provide a novel and improved method for ironing a shirt or similar garment in which portions are pressed by outwardly applied heated platens against a buck on which the garment is draped, and other portions are ironed from within by application of heated air that simultaneously distends the latter portions and passes therethrough.

Inasmuch as the pressing platens apply pressure to the front and back of the shirt that obviates displacement thereof, it is a further object of the invention to pre-inflate the distendable portions of the buck immediately before the platens are applied to achieve a wrinkle-free condition of the sides and yoke of the shirt and, then, after the platens are moved into pressing position, to fully inflate said distendable portions to iron the same from within, as above indicated.

A still further object of the invention is to provide novel and improved means to reciprocate a buck between dressing and pressing positions and, further, to provide a simple free-running buck-mounted carriage that, except for support and guide means, is disconnected from the machine while in motion between its dressing and pressing positions.

The invention also has for its objects to provide such

2

means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is an elevational view of a garment-pressing machine according to the present invention, the same being shown from the side opposite to the operator's side of the machine.

Fig. 2 is an enlarged plan sectional view as taken on line 2—2 of Fig. 1.

Fig. 3 is a vertical sectional view as taken on line 3—3 of Fig. 2.

Figs. 4 and 5 are plan sectional detail views, one below the other, of the middle right end of Fig. 2.

Fig. 6 is a vertical sectional view as taken on line 6—6 of Fig. 1 with the buck-mounted carriage in position between the pressing platens and preparatory to moving of said platens to pressing position.

Fig. 7 is a similar sectional view as taken on line 7—7 of Fig. 1, showing, however, only the operator's side of the machine.

Fig. 8 is a similar view as taken on line 8—8 of Fig. 1 and showing the opposite side of the portions shown in Fig. 7, the pressing platen that is shown being in pressing position against the buck.

Fig. 9 is an enlarged detail sectional view of the parts shown in the upper portion of Fig. 8.

Fig. 10 is an enlarged plan sectional view as taken on line 10—10 of Fig. 1 and showing the buck-mounted carriage in pressing position.

Fig. 11 is a similarly enlarged vertical sectional view as taken on line 11—11 of Fig. 1.

Fig. 12 is a fragmentary sectional view of a valve shown in Fig. 11.

Fig. 13 is a longitudinal fragmentary sectional view of coupling means connecting pressing air to the buck-mounted carriage when the latter is in pressing position.

Fig. 14 is a schematic view of the control and operating elements of the machine.

In this specification and in the appended claims, the term "shirt" is intended to include similar garments whether or not they have sleeves.

The shirt-body pressing machine that is illustrated comprises, generally, a rigid frame 20 that has track means 21 as part thereof, a carriage 22 mounted on and movable along said track means, means 23 to latch the carriage in shirt-dressing position at one end of frame 20, a buck 24 mounted on the carriage, means 25 to releasably clamp the tails of a shirt draped on said buck, means 26 to propel the carriage from its dressing to a pressing position, means 27 to provide a supply of heated air to the buck 24, means 28 to couple the air-supplying means 27 to the carriage 22, means 29 to couple said air-supplying means to the upper end of the buck 24, means 30 to release a buck-distending supply of air from the means 27 through the coupling means 28 and 29 as the carriage and buck arrive at the pressing position, means 31 to lock the carriage in pressing position, a pair of normally separated pressing platens 32 mounted on the frame, means 33 to move the normally separated platens toward each other when the dressed buck is positioned therebetween to effect ironing of the front and back of a shirt draped on the buck, means 34 controlled by the platen-moving means to

provide a supply of ironing air to the buck to press those portions of the shirt that are not engaged by the pressing platens, a source of compressed air 35, a controlling system 36 to provide air from said source to operate the means 26, 30, 31, 33 and 34, means 37 to propel the carriage from pressing position back to its dressing position, and a controlling system 38 to provide air from said source to operate means 37 and also restore the means 26, 30, 31, 33 and 34 to their initial condition preparatory to repetition of the cycle of operation of the machine.

The frame 20 is shown as comprising a relatively low end frame portion comprised of vertical members 40 connected at their upper ends by a cross member 41, and a pair of longitudinal base members 42 extending from members 40 to a relatively higher frame portion. The latter comprises front and back frame parts 43 (Fig. 6) of rectangular form, each said part comprising longitudinally spaced vertical members 44 and an intermediate member 45 rigidly connected to members 44 by upper longitudinal members 46 and intermediate members 47. The lower base portions of members 44 are connected by longitudinal members 48. These frame parts 43 are connected by upper and lower transverse members 49 and by an intermediate transverse member 50 that is at the level of cross member 41 (see Fig. 1).

The track means 21 is shown as comprising a pair of parallel horizontal transversely spaced tubes or pipes 51 carried at their ends by members 41 and 50 and extending therebetween.

The higher frame portion is provided with a longitudinal extension that is comprised of vertical members 52 connected at the ends of extensions of members 46 and 49 and further braced by intermediate longitudinal members 52a.

Formed in the above manner, frame 20 has a relatively low buck-dressing station portion 53 at one end, a relatively higher pressing station portion 54 at the middle, and a mounting portion 55 for the heated air-supplying means 27 at the opposite end, the track means 21 being common to station portions 53 and 54.

The carriage 22 comprises a body 56 arranged to span between tracks 51 and to be supported thereon by wheels 57. The carriage body 56 fixedly mounts a longitudinal tube 58 that is closed at end 59 and open at flanged end 60, the latter end being directed toward pressing station 54.

The means 23 is best seen in Fig. 4 and is shown as comprising a bracket 61 affixed to cross-member 41, a pair of grippers 62 mounted on pivots 63 on said bracket, spring-tensioned means 64 resiliently pressing the free ends 65 of grippers 62 together, and a roller 66 adapted to enter between ends 65 and to be resiliently and releasably held to hold the carriage in buck-dressing position.

The buck 24 is fixedly carried by the carriage 22 and extends upwardly from tube 58 in the plane of the longitudinal center of said tube. Said buck comprises a generally flat perforated hollow core 67 that is closed at its upper end 68 (Fig. 8) and open to the interior of tube 58, as best shown in Figs. 2 and 3. A layer or pad of steel wool or similar porous and resilient material 69 is applied over the opposite sides of perforated core 67 and the same is covered with a fabric layer 70 of fine mesh material, of which nylon fabric is an example. It will be clear from the foregoing that air introduced into tube 58 will enter the hollow of the core and pass through the perforations thereof and through the pores of pad 69 and the interstices of fabric cover 70.

The height of this padded core is such that a shirt draped thereon, with the back against one face and the front against the other, has its tails disposed against the lower portion of the core. The width of said core is such that said front and back of the shirt may be centered thereon with the sides laterally overstanding the side edges 71 of said core.

The buck 24 further includes a pair of fabric top-

closed tubular shirt-side pressing members 72 that are connected at 73, at their lower ends, to tube 58. Said tubular members 72 may be connected to the lateral edges of the buck core by suitable spaced tack points and serve as inflatable flanking side extensions of said core. Nylon fabric is preferred as the material of which said tubular members are made, the fine interstices of this fabric permitting passage of air supplied by tube 58 to the sides of a shirt draped thereover. Thus, a shirt draped on the buck has its sides held in extended and wrinkle-free condition by tubular members 72 and is subjected to the inwardly applied ironing force of the heated air introduced into tube 58.

Shirt-side spreading bars 74 may be pivotally carried by the sides of the buck core as on arms 75. After draping the shirt on the buck, the operator may outwardly extend these bars by depressing handles 76 to outwardly stretch the shirt sides and remove any deep creases there may be in said sides. These bars may then be returned to collapsed position closely adjacent the core edges.

Along its upper end, the buck is provided with an end-closed tubular yoke-pressing member 77 which has a central air inlet tube 78 affixed to a collar-clamping form 79 provided on the core and extending forwardly from the face of the buck against which the shirt-front is applied. The form 79 is generally conventional and is here used to support tube 78. Tubular member 77 is made of the same material as are tubes 72 and by suitable tacks 80 is affixed to the padded core so that introduction of heated air through tube 78 results in inflation thereof as shown best in Fig. 9. The closed ends 81 of tubular member 78 extend laterally beyond the side edges of the core, as best seen in Fig. 1, and are held extended by flexible arms 82 which are preferably angularly upwardly directed. It will be noted that tube ends 81 together with arms 82 serve to support the yoke of a shirt to the arm holes therein and that the extending portions of said arms 82 support the shirt sleeves adjacent said arm holes. The remainder of the sleeves may hang pendent off the ends of arms 82.

The form of tubular member 77 is made so as to conform, when inflated, to the downward slope, from the middle outward, of a shirt yoke and so that such yoke is subjected to the inwardly applied ironing force of heated air introduced into tube 78 and which inflates tube 77.

As will be seen from the foregoing, buck 24 essentially comprises a rigid core having compressible and porous faces, and inflatable side and yoke portions. While it is preferred to form member 77 separate from members 72 and to provide an independent introduction of heated air into said member 77, it will be obvious that a single tubular member extending along the sides and across the top of the core may be used and that the heated pressing air may be introduced only through tube 58. The reason for the indicated preference is that a shirt yoke is usually made of two plies of material and either requires longer pressing time or greater heat than is applied to the single-ply shirt sides. By a separate introduction of heated air to member 77, air may be used in this member at a higher temperature than in members 72 so that the pressing time for the double-ply yoke and the single-ply sides will be the same and the timing of the pressing cycle facilitated accordingly.

The means 25 is shown as a clamp member 85 on the end of an arm 86 on a shaft 87, and clamp plate members 88 on a shaft 89. Clamp members 85 and 88 are on opposite sides of the buck, as best seen in Fig. 3, as are their mounting shafts 87 and 89.

Arm 86 constitutes one arm of a bellcrank lever 90 that is connected to a link 91 which extends through the carriage body 56. Clamp plate 88 constitutes an arm of a bellcrank lever 92 which extends through buck core 67 in the same direction as lever 90 and is connected to a link 93 which also extends through carriage body 56. Since

lever arms 90 and 92 are on the same side of the carriage and shafts 87 and 89 on opposite sides, an upward push on link 91 is required to press clamp member 85 against one face of the buck and a downward pull on link 93 is required to press clamp plate 88 against the opposite face of the buck.

Treadle-operated means are provided on the operator's side of the machine to effect such clamping movement of members 85 and 88. To push upwardly on link 91 there is provided a treadle 94 pivoted at 95 and held raised by a spring 96 anchored at its upper end to a strap frame 97. A bellcrank lever 98, pivoted at 99 to said frame 97, has one arm connected by a link 100 to said treadle and the other arm engaged with and adapted to raise a link pusher 101 that is vertically aligned with link 91 when the carriage is in dressing position. To pull downwardly on link 93 there is provided a second treadle 102, also pivoted at 95 and held raised by a spring 103 anchored at its upper end to a strap frame 104. A puller link 105 is connected to treadle 102, extends upwardly through frame 104, and is provided at its upper end with a bifurcated yoke 106 aligned with link 93. Said link extends through the bifurcation in said yoke and has a head 107 on the lower end thereof.

From the foregoing, it will be seen that depression of treadle 94 will move clamp member 85 to clamping position by pushing up on link 91 and that depression of treadle 102 will move clamp plate 88 to clamping position by pulling down on the head 107 of link 93. Since link pusher 101 and link 91 are normally disconnected and the bifurcation in yoke 106 is laterally open, the carriage may be moved toward pressing position after the clamp members 85 and 88 have been operated. By passing links 91 and 93 through suitable apertures in levers 108 that are pivoted at 109 and weighted at their free ends 110, said links are frictionally latched or clutched by said levers 108 to retain the clamping positions thereof.

In order to clamp the tails of a shirt draped over the buck, the operator need merely depress treadles 94 and 102 since levers 108 effect automatic clutching of links 91 and 93 to retain clamping position of clamp members 85 and 88. This position is retained during movement of the carriage to pressing position. Only after the carriage has returned to its initial position will the clutch levers 108 be raised so as to effect release of links 91 and 93 and of the clamping members 85 and 88. To this end, a cam 111, carried on a bar 112 from cross member 41, is placed in the path of movement of the weighted end of levers 108 to raise the same on their pivots 109. Cam 111 is mounted to depress when the levers 108 move therewith toward pressing position so as not to disturb the clutching engagement with links 91 and 93, and not to depress upon return movement of the carriage to effect automatic declutching. In any case, weights 110 may be manually flipped up after return of the carriage and cam 111 dispensed with.

The means 26 comprises an air cylinder 113 provided with a piston 114 having a stem 115 that is directed toward the pressing station of the machine. A pusher head 116 is provided on the end of said stem. It will be clear that admission of pressure fluid into cylinder 113 will cause projection of stem 115 and that the head 116 thereof will strike against the carriage body 56 and propel said carriage and the dressed buck thereon along track means 21. The means 26 is best seen in Figs. 1, 5 and 14.

The means 27 that supplies heated air that is used in the buck 24 is shown at the left end of Fig. 1 and, in part, in Figs. 11 and 12. Said means 27 is shown as comprising an air compressor 120 connected by a suitable drive 121 to an electric motor 122. Said compressor is provided with an air inlet 123, that is preferably fitted with an air cleaner 124, and with an air outlet 125 that conducts air compressed by the compressor to a valve 126. A by-pass conduit 127 by-passes the compressor to directly connect air inlet 123 and valve 126. The valve 75

126 is provided with a compressed air outlet 128 that enters a tank 129 provided with conventional means 130 to heat the air supplied thereto. Tank 129 is provided with an outlet 131.

5 Valve 126 has three ports connecting respectively to the outlet 125 from the compressor, the by-pass 127, and the outlet 128. Said valve is provided with a port-controlling vane 132, on a shaft 133, which normally closes outlet 128. Accordingly, until said vane is moved the 10 air compressed by compressor 120 is circulated through by-pass 127. Upon moving said vane to wholly open outlet 128 or partially open the same, compressed air enters tank 129 and then exits from outlet 131. During partial opening of outlet 128, a relatively small flow of compressed air enters tank 129, the remainder circulating in by-pass 127.

The means 28, best seen in Fig. 13, effects coupling of air outlet 131 and tube 58 on carriage 22. When the latter is propelled to pressing position, the flanged end 60 20 of tube 58 telescopically engages an extension 134 on a fitting 135 telescopically fitted in the end of outlet 131. A flange 136 on fitting 135 is engaged by flange 60 and effects contraction of a set of springs 137 that normally project said fitting toward tube 58. In this manner, a 25 resilient and effective coupling between air outlet 131 and tube 58 is made, when the carriage is at pressing position, to provide the core 67 and tubes 72 of the buck 24 with heated air from tank 129.

The means 29, best seen in Figs. 6 to 9, effects coupling of air outlet 131 and tubular member 77 of buck 24. When the carriage is propelled to pressing position, the forwardly-directed tube 78 of said member 77 is brought into alignment with the flanged end 140 of a pipe 141 that has a flexible portion 142 connected to an 30 auxiliary air-heating tank 143. The latter is connected by a conduit 144 with outlet 131 and is provided with its own air-heating means 145 of conventional form. In this manner, heated air from tank 129 is supplied to auxiliary tank 143, further heated therein, and discharged 35 from flanged end 140 of pipe 141.

The means 29 further includes a suspender 146 which is mounted on cross member 49 of the frame and is connected to pipe 141. Said suspender is shown as an articulated parallelogram adapted to swing in a transverse plane so that the flanged end 140 of pipe 141 may be brought into and out of engagement with the open end 40 of tube 78 when the buck is in pressing position. As before explained, the yoke of a shirt on the buck is two-ply. Accordingly, the heated air from tank 129, being 45 additionally heated in auxiliary tank 143, subjects said yoke to inwardly applied pressing heat that is greater than that applied to the single-ply sides of said shirt. It is a simple matter, therefore, to regulate the heated air in tubular member 77 relative to that in the tubular members 72 to achieve proper pressing of the sides and 50 poke of a shirt in the same time.

When the buck-mounted carriage is propelled by the means 26 to pressing position, the means 30 is actuated by the carriage as the same arrives at pressing position to release from the heated air supplying means a relatively small amount of air that has the purpose of distending tubular members 72 and 77 so that creases and wrinkles in the sides and yoke of the shirt are removed. Said means 30 (see Fig. 10) comprises a cam 147 on the carriage body 56, a bellcrank lever 148 on a pivot 60 149 in a bracket 150 affixed to one member 45 of the machine frame, a roller 151 on the end of one arm of said lever and in the path of movement of cam 147, and a piston valve 152, carried by said bracket, operable by the other arm of said lever when rocked on its pivot by said cam. The hereinafter description of control system 36 will disclose how operation of said valve 152 causes movement of vane 132 from the position closing outlet 128 to position 132a in which said outlet is partly 65 opened.

The means 31, shown best in Fig. 10, comprises an air cylinder 153 that is mounted on bracket 150 and is controlled by valve 152. Said cylinder has a projectable stem 154 on the end of which is carried a locking dog 155 which, from a retracted position, is projected behind roller 66 on carriage 22 as the latter arrives at pressing position. A roller 156 guides dog 155 and an adjustable stop 157 limits the projected position of said cam; as will be later seen, return of said dog to retracted position is effected by spring 158.

The pressing platens 32 are substantially alike except that one of them is provided with an upper notch 159 to accommodate the collar clamp 79 and tube 78 on the buck. Each platen, as best seen in Fig. 9, is internally hollow to receive steam as through an inlet 160 (Fig. 1). These platens are flat and at least large enough in both dimensions to effect pressing engagement with the front and back of a shirt draped on padded core 67. In practice, the side portions of the platens overstand tubular members 72 and the upper portions overstand tubular member 77 so as to press against the fronts and backs of said tubular members while the same are inflated. Such pressure flattens said members 72 and 77 as permitted by the elasticity of the air therein and further improves the ironing effect on the sides and yoke of a shirt on the buck.

Each platen 32 is mounted on two pairs of links 161 pivotally mounted at 162 on vertical frame members 44 and pivotally connected to said links at 163. The platens hang on said links 161 and normally are separated, because of their pendent mount, to provide ample space to receive buck 24 between them, as shown in Fig. 6. Each platen is provided with an outer rigidifying frame 164 and with a pair of vertically disposed outwardly extending plates 165, preferably positioned midway between the sides edges of the platen and affixed to said frame 164.

The means 33 to move the platens 32 into pressing engagement with the buck is best seen in Figs. 1, 7 and 8. Since said means is substantially the same for each platen, only one need be described.

The means 33 comprises an air cylinder 166, mounted on member 45 of the frame, and provided with a piston 167 that is upwardly projectable by compressed air, as will later be described. A stem 168 of said piston extends upwardly and mounts a cam 169. One side of said cam is flat and engaged with guide rolls 170 mounted on member 45 of the frame. The opposite side of said cam is engaged by a cam roll 171 carried by and between plates 165 of the platen. Said latter side of the cam has a rise 172 that is quite abrupt and a more gradual rise 173 extending from rise 172.

When the cam is retracted, platen 32 may hang pendent on its links 161 with cam roll 171 engaged against the low part of rise 172. As the cam is upwardly projected, abrupt rise 172 will quickly move the platen into light engagement with buck core 67. Then, as the more powerful gradual cam rise 173 engages roll 171, as in Fig. 8, substantial force is applied to press the platen tightly against the padding of said buck core. Upon retraction of said cam 169, the platen will gravitationally fall toward the pendent position of Fig. 6. In order that such fall not be free with possible resulting damage to the parts, a friction drag snubs the fall to make the same more gradual. Such a drag is shown in Figs. 7 and 8 and comprises a pair of brake shoes 174, engaged with a stud 175 on platen plates 165, and pivotally mounted at 176 on frame members 45. The drag of the brake shoes 174 may be regulated by a spring 177.

It will be recalled that air tube 141 normally has a retracted position to allow tube 78 to align therewith, as shown in Fig. 6. The movement of the platen that has notch 159 is utilized to move said tube 141 into and out of air-passing engagement with tube 78. To this end, tube 141 is provided with spaced lugs 178 and 179 be-

tween which is disposed a roller 180 on the end of an arm 181 pivotally carried at 182 by platen plates 165. A spring 183 biases arm 181 in a direction toward lug 179 and a stop 184 limits such movement of arm 181.

When the platen 32, that mounts said arm 181, is retracted, stop 184 positions said arm so that its roller 180 engages lug 178 to hold tube 141 retracted. As the platen is moved to pressing engagement with the buck, roller 180 on arm 181 leaves lug 178, picks up lug 179, and shifts tube 141 on its suspender 146 in a direction to engage against the open end of tube 78. Since arm 181 is resiliently mounted, it will yield on its pivot 182 after such engagement of tubes 78 and 141 while cam rise 173 may create additional movement of the platen. Upon return to pendent position of the platen, stop 184 will cause arm 181 to re-engage lug 178 and return tube 141 to retracted position spaced from tube 78.

When the platens are moved to pressing position by upward projection of pistons 167 of cylinders 166, a port 185 in an intermediate port of one of said cylinders is uncovered by its piston and allows pressure air that is projecting said pistons to operate a piston valve 186 to conduct pressure air to the means 34 that supplies heated pressing air to buck 24.

With particular reference to Figs. 11, 12 and 14, the means comprises the mentioned valve 126, an arm 187 on the shaft 133 on which the port-controlling vane 132 is mounted, a bracket 188 carried by frame members 189, a link 190 pivotally mounted at 191 to said bracket, a link 192 pivotally connected at 193 to the end of arm 187 and pivotally connected at 194 to link 190, a spring 195 exerting its force in a direction to hold links 190 and 192 in an over-center position with respect to a straight line extending between pivots 191 and 193, a spring 196 pulling downward on arm 187 in a direction tending to straighten links 190 and 192, an air cylinder 117 having a stem 198 directed, when projected, to break the over-center disposition of toggle links 190 and 192, and an air cylinder 199 having a stem 200 pivotally connected to arm 187. The manner of operation of this device will be explained in the description of systems 36 and 38.

The source of compressed air 35 comprises an air inlet 201 that is connected to valves 202 and 203, both of which are normally closed. Valve 202 is the valve that is opened by the operator, after buck 24 is dressed, to move the carriage to pressing position. This valve, when open, communicates air inlet 201 with piston 113, through a line 204 and with a diaphragm 205, through a line 206. The air inlet 201 has a direct connection 207 to a piston valve 208 and a direct connection 209 to a piston valve 210. Valve 203 is the control that returns the carriage to dressing position and may be either manually operated or time controlled, as desired. Said valve, when open, communicates inlet 201 with a diaphragm 211, through a line 212.

Valve 208 controls and is controlled by mechanism that includes toggle linkage 213 and said diaphragms 205 and 211. Valve 210 controls and is controlled by toggle linkage 214 and diaphragms 215 and 216.

The means 37 is similar and opposite to means 26 and comprises a cylinder 217 having a piston 218 provided with a stem 219 and a head 220 on the end of said stem. This means is controlled by a piston valve 221 mounted on one frame member 55 and, through an actuating arm 222, the piston of said valve is controlled by a projection 223 on plates 165 of the corresponding platen 32 when the latter returns to the separated position from pressing position.

The system 36 operates in the following manner: Compressed air line 201 brings pressure air to control valve 202, piston valves 208 and 210. Manual opening of valve 202 causes projection of stem 115 of means 26 and, at the same time places pressure through line 206 on diaphragm 205. The latter, through stem 224, breaks toggle linkage 213 to open valve 208 so that pressure air

from line 207 may be conducted, through said valve 208, to piston valve 152 and to a similar valve 225. An air line 226 connects valve 208 to valves 152 and 225.

When the buck-mounted carriage is propelled by projection of piston 115 toward pressing position, the cam 147 on said carriage operates piston valve 152, through bellcrank lever 148, to open lines 227 and 228 to pressure in line 226. Line 227, being connected to cylinder 153, the pressure in said line causes projection of stem 154 and the locking dog 155 thereon to effect locking of the carriage in pressing position at station 54. Since line 228 is connected to cylinder 199, simultaneously with locking of the carriage, pressure from line 226 is conducted to said cylinder by line 228 to cause projection of stem 200 of said cylinder. Because the over-center linkage 190, 192 is resisted by stem 198 of cylinder 117, stem 200 can move valve arm 187 through only a relatively small arc so that valve vane 132, from the position closing outlet 128, is moved to position 132a (Fig. 12) whereby outlet 128 is open to passage of a small amount of air compressed by compressor 120. Thus, as the buck arrives at pressing station 54, the tubular members 72 and 77 are distended to stretch out wrinkles in the shirt sides and yoke.

At the instant that locking dog 155 has locked the carriage, the projection of stem 154 opens a line 229 to the pressure of line 227 and allows such pressure to operate a diaphragm 230 that controls piston valve 225. Since the latter valve has pressure air supplied thereto by line 226, the stem 231 of diaphragm 230 opens a line 232 to pressure from said line 226. Line 232 is connected to cylinders 166. Therefore, at the instant locking dog 155 has locked the carriage, pistons 167 will be projected causing cams 169 to move the pressing platens 32 toward each other and in pressing engagement with the front and back of a shirt draped on buck 24.

A branch line 233 connects line 232 with piston valve 186. Thus, when port 185 is opened during platens-moving projection of pistons 167, a diaphragm 234 is actuated by air from one of the cylinders 166 and the stem 235 of said diaphragm actuates valve 186 to open a line 236 to the pressure of branch line 233 which is connected to cylinder 117. It will be seen, therefore, that, during movement of platens 32 to pressing position and before port 185 is uncovered, the valve 126 is partly opened to supply the initial air that distends tubular members 72 and 77.

When line 236 is opened to air pressure, the platens 32 are in or very close to pressing position. Thus, when stem 198 of cylinder 117 is projected by air from said line 236, to break the toggle or over-center condition of links 190 and 192, said initial inflating air is first shut off as the toggle links move past their dead center and then, as the toggle folds up, the air pressure in cylinder 199 becomes effective to swing arm 187 in a direction to move van 132 to position 132b. Thus, outlet 128 is fully opened and by-pass 127 closed to conduct the entire output of the compressor 120 to tubes 58 and 78, it being realized that, at this time, said tubes have been coupled by the means 28 and 29 to the supply of heated air from tank 129 and as further heated in tank 143. The supply of heated air to tubular members 72 and 77 is continued while the platens 32 press the front and back of the shirt to effect complete ironing of the same. Since the air supplied to member 77 is hotter than the air supplied to members 72, the pressing time for the different portions of the shirt can be made to be the same.

When such pressing time is ended, valve 203 is opened to set system 38 into operation. Opening of line 212 to pressure from inlet line 201, causes actuation of diaphragm 211 so that its stem 237 re-sets toggle linkage 213 which operates valve 208, shutting off air pressure in line 226 and, thereby, stopping the supply of air to valves 152 and 225. All the valves and cylinder pistons of the systems 36 and 38, except pistons 114 and 218, are either spring loaded or weighted to return to their ini-

tial positions and, when so returned, exhaust through ports 238. Consequently, when valve 208 is closed, valve 225 exhausts line 232 to allow pistons 167 to return to initial position withdrawing cams 169 and allowing platens 32 to separate. At the same time, valve 152 exhausts cylinder 153 allowing spring 158 to retract locking dog 155 to free carriage 22.

Upon return of the platens to their initial separated position, projection 223 on one platen, through actuating arm 222, opens valve 221 to pass pressure air from line 209 through open valve 210 and, through lines 239 and 240, to cylinder 217. The resultant projection of stem 219 causes propulsion of the carriage from pressing station 54 back to dressing station 53 where gripping or latch means 23 receives and holds the carriage stationary.

As piston 218 of cylinder 217 opens a line 241, pressure from line 240 is conducted to said line 241 to cause actuation of diaphragm 216. At the time that stem 200 was projected to fully open valve 126, valve 199 communicated line 228 with a line 242 connected to diaphragm 215 which was actuated to throw toggle 214 and open piston valve 210 to conduct pressure air from line 209 to valve 221 by way of line 239. Therefore, when line 241 is opened, diaphragm 216 restores the toggle 214 to its initial position and closes valve 210, allowing the same to exhaust through its port 238, and shutting off the supply of air to valve 221 and to piston pusher means 37.

In the above manner, the cycle of operation is completed. Thereafter, the operator removes the pressed shirt from buck 24, replaces the same with a shirt to be pressed, and institutes the operation as before.

The buck 24 is shown with flat sides which, of course, may be modified to be convexly bowed and the pressing platens 32 formed to conform thereto. Therefore, the term "generally flat" as applied to the buck in the description and the appended claims is intended to include such modification of the buck.

While I have illustrated and described what I now contemplate to be the best mode of carrying out my invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. A shirt-body pressing machine comprising, in combination, a frame having a dressing station and a pressing station, track means extending through both said stations, a carriage movable along the track means, a generally flat shirt-mounting buck on said carriage, said buck being provided with air-passing inflatable portions, means to move the carriage and the buck thereon from the dressing to the pressing station, a normally-closed source of heated shirt-pressing air, means to couple said source of air to the inflatable portions of the buck when the carriage is at the pressing station, means controlled by the carriage, when the same arrives at the pressing station, to partly open said source of heated air to inflate said inflatable portions and, thereby, smooth out wrinkles in those parts of the shirt engaged over the inflatable portions, a pair of heated pressing platens at the pressing station and normally spaced to receive the buck therebetween, means to move said platens to pressing position against the front and back of the shirt disposed against the flat sides of the buck, means to simultaneously fully open said source of heated air to simultaneously subject all portions of the shirt-body engaged with the buck and with the inflatable portions thereon to the pressing heat of the heated air and of the platens, means to separate the platens after the shirt-body has been pressed, and means controlled by one of the platens as 70 the same moves to separated position to move the car-

riage and the shirt-mounting buck thereon back to the dressing station.

2. A shirt-body pressing machine according to claim 1: said inflatable portions comprising tubular members flanking the buck and engaged by the sides of the shirt and a tubular member across the top of the buck and engaged with the yoke of said shirt and auxiliary air heating means in the path of flow of heated air to the latter tubular member to provide the same with yoke-pressing air at a temperature higher than the pressing air provided in the first-mentioned tubular members.

3. A shirt-body pressing machine according to claim 1: carriage-locking means, controlled by the means that partly opens the source of heated air, to hold the carriage immovable in the pressing station.

4. A shirt-body pressing machine according to claim 1: treadle-operated means at the dressing station, and means mounted on the carriage and operable by said treadle-operated means to releasably clamp the tails of a shirt draped on the buck to the opposite flat faces of said buck.

5. A shirt-body pressing machine according to claim 1: treadle-operated means at the dressing station, and means mounted on the carriage and operable by said treadle-operated means to releasably clamp the tails of a shirt draped on the buck to the opposite flat faces of said buck, said latter means including automatic latches, and means carried by the frame to release said latches upon return of the carriage to the dressing station.

6. A shirt-body pressing machine according to claim 1: means mounting the carriage for free movement along the track means in both directions, and said two carriage-moving means comprising pusher members that propel the carriage between the dressing and the pressing stations.

7. A shirt-body pressing machine according to claim 1: means mounting the carriage for free movement along the track means in both directions, said two carriage-moving means comprising pusher members that propel the carriage between the dressing and the pressing stations, and a latch to grip and hold the carriage immovable while at the dressing station.

8. A machine for pressing shirt bodies and the like, said machine comprising, in combination, a frame having a dressing station at one end and a pressing station at the opposite end, horizontal, straight track means extending through and between the stations, hollow buck means adapted to mount a shirt body and movable along the track means between said two stations, means to move

the buck means from one station to the other, said latter means located at each end of the track means and being opposed to each other, means to operate said opposed means alternately to move the buck means along the track means first in one direction and then in the other, a normally-closed source of heated shirt-pressing air, means to couple said source of air to the buck when the carriage is at the pressing station, a pair of pressing platens at the pressing station and normally spaced to receive the buck therebetween, and means to move the pressing platens to pressing position against the front and back of a shirt draped on said buck means.

9. A machine for pressing shirt bodies and the like, said machine comprising, in combination, a frame having a dressing station at one end and a pressing station at the opposite end, horizontal, straight track means extending through and between the stations, hollow buck means adapted to mount a shirt body and movable along the track means between said two stations, means to move the buck means from one station to the other, said latter means located at each end of the track means and being opposed to each other, means to operate said opposed means alternately to move the buck means along the track means first in one direction and then in the other, 15 a normally-closed source of heated shirt-pressing air, means to couple said source of air to the buck when the carriage is at the pressing station, the buck means being provided with inflatable portions, means controlled by the buck means, when at the pressing station, to partly open said air source to cause inflation of the inflatable portions for smoothing wrinkles in parts of the shirt body engaged over said portions, a pair of pressing platens at the pressing station and normally spaced to receive the buck therebetween, means to move the pressing platens to pressing position against the front and back of a shirt draped on said buck means, and means to simultaneously fully open said source of air to subject all portions of the shirt body engaged with the buck means to the heat of said air.
